UNITED STATES PATENT OFFICE.

CHARLES L. BASTIAN, OF CHICAGO, ILLINOIS.

BOWLING-ALLEY-PIN SPOTTER.

No. 812,253.

Specification of Letters Patent.

Patented Feb. 13, 1906.

Application filed December 27, 1904. Serial No. 238,517.

To all whom it may concern:

Be it known that I, CHARLES L. BASTIAN, a citizen of the United States, residing at Chicago, in the county of Cook and State of Illinois, have invented new and useful Improvements in Bowling-Alley-Pin Spotters, of which the following is a specification.

This invention relates to bowling-alley-pin spotters; and its object is to facilitate the setting-up operation and to spot the pins mechanically in correct position on the spots on the alley-bed.

Further objects of the invention are to provide an apparatus of this character which shall be simple in construction, light in weight, and easily operated, which will not injure the alley-bed, and which can be used even if some pins remain standing on the alley-bed.

In the accompanying drawings, which illustrate one manner of embodying the invention, Figure 1 shows the apparatus in elevated position above the alley-bed. Fig. 2 is a detail sectional view showing the positioning devices for one pin. Fig. 3 is a similar detail sectional view showing the apparatus at rest on the alley-bed and the positioning-shoes spotting a pin. Fig. 4 is a detail sectional view of another form in which the guide-blocks for the shoes are omitted. Fig. 5 is a detail view showing one of the guides at the rear of the spotter. Fig. 6 shows the apparatus in lowered position, but not resting on the alley-bed, and the raising means. Fig. 7 is a plan view of the spotter, showing the guide-rods in section.

The spotter is preferably constructed in triangular shape to correspond with the arrangement of the pins, and it comprises the top plate 10 and bottom plate 11, which are provided with registering openings 10' 11' to receive the pins. Sleeves 12 are suitably fastened to the top plate 10, and guide-rods 13 are connected at their lower ends to the bottom plate and extend upward through said sleeves to the top plate and through one or more guides 14, suitably mounted at the sides of the alley.

Two or more positioning-shoes 15 are operatively arranged beneath the top plate and around each of the pin-openings therein, and the faces of these shoes are preferably shaped to fit, more or less, the body of the pin, as shown in Fig. 3. These shoes can be pivotally suspended at 15' from the top plate, and their lower ends 16 are rounded, so that they

will slide easily thereon and swing into closed position to receive the pin when they engage the bottom plate. I prefer to provide blocks 17 on the bottom plate with inclined faces 18, which are engaged by the heels 19 of the shoes and which compel the inward movement of the shoes as the latter move downward against the bottom plate. The blocks, which form guides for the shoes, may be dispensed with, as shown in Fig. 4, and the shoes caused to move inwardly solely by the engagement of their rounded ends with the bottom plate.

The apparatus can be raised in any suitable manner, and in Fig. 6 I have shown ropes 20 attached to the spotter and passing over pulleys 27, fastened to the ceiling 28 and connected at their ends to a counterweight 29, which assists in raising the spotter and prevents it from descending too quickly. When the apparatus is elevated, the bottom plate is suspended below the positioning-shoes, Figs. 2 and 4, and this relative position of the bottom plate to the shoes is maintained by adjustable locking-collars 21 on the guide-rods 13 above the top plate.

The apparatus may be adjusted so that the bottom plate will engage and rest upon the alley-bed, which then forms a support for the apparatus, as shown in Fig. 3; but if it is not desired that the apparatus shall so engage the alley-bed the nuts 23 may be screwed down on the rods 13, Fig. 1, so that the apparatus will be suspended above the alley-bed 90 when in lowered position by the nuts 23, resting upon the guides 14. Any other stops serving the purpose of the nuts 23 may be employed, and likewise any other means may be used for accomplishing the purpose of the adjustable locking-collars 21 and the sleeves 12.

To protect the positioning devices from balls accidentally thrown while the apparatus is in lowered position, I prefer to provide the apparatus with sides 24, which are fastened to the top plate. I also prefer to provide one or more guides 25 at the back of the apparatus, which are arranged to enter sockets 26 in the alley-bed or in the pit back of the bed, these guides and sockets being preferably of triangular shape, as shown in Fig. 5.

The operation of my improved spotter will be readily understood. When some or all of the pins have been removed from the alley-bed, the spotter will be lowered until it comes to rest upon or just above the alley-bed, as previously described. When the bottom

plate comes to rest, the top plate will continue its downward movement until the shoes have moved inwardly from the open position shown in Fig. 2 to closed position, (shown in Fig. 3,) at which time they are ready to receive and spot the pins. The pins are then thrown into the openings, and after they have all been so arranged the spotter is raised to its elevated position. (Shown in Fig. 1.) When the spotter starts to move upward, the shoes will open by gravity and clear the pins without shaking or moving them from the spots on the alley-bed. The apparatus will be constructed and mounted for operation so that the positioning devices will operate automatically to position the pins correctly upon the spots on the alley-bed and leave them in such position when the spotter is elevated.

My improved spotter is simple in construction, light in weight, and can be easily operated by any pin-boy. Its use relieves the pin-boy of the necessity for spotting the pins, his only duty being to raise and lower the spotter and throw the pins into the spotter when in lowered position. This enables setting and spotting of the pins to be accomplished very quickly, and as the pins are mechanically and correctly spotted in the first instance the game can be played without the usual delay and annoyance caused by pin-boys working slowly and incorrectly spotting the pins. Besides facilitating the setting-up operation my invention is particularly valuable because it insures absolutely correct spotting of the pins, and thus eliminates all chance of the pins being purposely spotted incorrectly. After the pins are spotted, the spotter is elevated and the player has an unobstructed view of the pins, and the pin-boy can step to one side and avoid the thrown ball and the pins which may be knocked down. As the positioning devices are normally open and do not close until the bottom plate is brought to rest, it does not matter if some pins remain in upright position on the alley-bed, for the spotter can be lowered upon the upright pins if the upper ends thereof will enter the openings in the bottom plate. The collars 21 serve to lock the top and bottom plates together, so that the bottom plate will move upward with the top plate when the spotter is raised.

Without limiting myself to the exact construction and arrangement of parts herein shown and described, what I claim, and desire to secure by Letters Patent, is—

1. In a vertically-movable pin-spotter for bowling-alleys, normally open movable positioning devices, and means forming part of the movable spotter and normally out of operative engagement with said devices and movable relatively thereto for engaging and moving said devices into closed position to receive the pins.

2. A vertically-movable pin-spotter for

bowling-alleys, comprising movable positioning devices constructed to open by gravity when the spotter is raised, and means forming part of the movable spotter for closing said devices to receive the pins, said devices and means being normally out of operative engagement and said means being adapted to engage and move the devices into closed position when the spotter is lowered to receive the pins. 75

3. A vertically-movable pin-spotter for bowling-alleys, embodying movable positioning devices, and means forming part of the movable spotter and located beneath said devices and normally out of operative engagement therewith for moving them into closed position to receive the pins. 80

4. A vertically-movable pin-spotter for bowling-alleys, comprising movable positioning devices, and a plate beneath said devices and movable relatively thereto for moving them into closed position to receive the pins. 85

5. In a vertically-movable pin-spotter for bowling-alleys, normally open pivoted positioning devices, and means forming part of the movable spotter and normally out of operative engagement with said devices and movable relatively thereto for engaging and swinging said devices into closed position to receive the pins. 90

6. A vertically-movable pin-spotter for bowling-alleys, embodying pivoted positioning devices, and means beneath said devices and normally out of operative engagement therewith and movable relatively thereto for engaging and swinging them into closed position to receive the pins. 95

7. A vertically-movable pin-spotter for bowling-alleys, comprising pivoted positioning devices, and a plate beneath said devices and movable relatively thereto for moving them into closed position to receive the pins. 105

8. A vertically-movable pin-spotter for bowling-alleys, embodying movable positioning devices, means for supporting said devices, and means normally out of operative engagement with said positioning devices and movable relatively thereto and adapted to engage and move said devices into closed position. 110

9. A vertically-movable pin-spotter for bowling-alleys, embodying movable positioning devices, means for supporting said devices, and a plate beneath the positioning devices and movable relatively thereto, said devices and plate being arranged to engage each other when the spotter is lowered to move the devices into closed position to receive the pins. 115

10. A vertically-movable pin-spotter for bowling-alleys, comprising a bottom plate, a top plate, one of said plates being movable relative to the other, and movable positioning devices suspended from the top plate and adapted to engage the bottom plate and be 120

130

moved thereby into closed position to receive the pins.

11. In a vertically-movable pin-spotter for bowling-alleys, the combination of a bottom plate, a top plate, a fixed stop for limiting the downward movement of the bottom plate, and movable positioning devices carried by the top plate and adapted to engage the bottom plate and be moved thereby into closed position to receive the pins.

12. In a vertically-movable pin-spotter for bowling-alleys, the combination of two plates spaced apart one above the other and provided with openings to receive the pins, one of said plates being movable relative to the other, and normally open movable positioning devices arranged between said plates and adapted to be moved to closed position during the continued downward movement of said relatively movable plate by engagement with the other plate after it has come to rest.

13. In a vertically-movable pin-spotter for bowling-alleys, the combination of two members spaced apart one above the other, and movable toward and from each other and provided with openings to receive the pins, normally open movable positioning devices suspended from the under side of the top member and adapted to engage the bottom member, and a fixed stop for limiting the downward movement of the bottom member.

14. In a vertically-movable pin-spotter for bowling-alleys, the combination of two members spaced apart one above the other and movable toward and from each other and provided with openings to receive the pins, normally open movable positioning devices suspended from the under side of the top member, and guides on the bottom member

arranged to be engaged by the positioning devices when said members move toward each other.

15. In a vertically-movable pin-spotter for bowling-alleys, the combination of two members spaced apart one above the other and movable toward and from each other and provided with openings to receive the pins, normally open movable positioning devices suspended from the under side of the top member and adapted to engage the bottom member, guides on the bottom member beneath the positioning devices, and a fixed stop for limiting the downward movement of the bottom member.

16. In a pin-spotter for bowling-alleys, the combination of a vertically-movable plate, rods connected to said plate and guided at the sides of the alley, devices for adjusting the downward movement of said plate, and movable positioning devices supported above said plate and movable vertically with and adapted to engage said plate.

17. A vertically-movable pin-spotter for bowling-alleys, comprising movable positioning devices constructed to open by gravity when the spotter is raised, means for raising the spotter to clear the pins, and a single means forming part of the movable spotter and normally out of engagement with said positioning devices for simultaneously engaging and moving all of said devices into closed position to receive the pins when the spotter is lowered.
